FOLDABLE DISPLAY

Sidney Godell, Chicago, Ill., assignor to Arvey Corporation, Chicago, Ill., a corporation of Illinois

Application May 26, 1939, Serial No. 275,788

5 Claims. (Cl. 248—152)

This invention relates to improvements in foldable displays and refers specifically to a foldable cardboard display which is held in display position by, and is adapted to prominently exhibit a bottle.

The objects and advantages of my invention will be apparent from the accompanying drawings and following detailed description.

In the drawings,

10 Fig. 1 is a development of my improved display.

Fig. 2 is a front elevational view of the display piece in display position.

15 Fig. 3 is a side sectional view of the display taken on line 3—3 of Fig. 2.

Fig. 4 is a top plan view of the display.

Fig. 5 is a fragmentary detailed sectional view of a portion of the base of the display.

20 Fig. 6 is a sectional view taken on the line 6—6 of Fig. 5.

Referring in detail to the drawings, with particular reference to Fig. 1, 1 indicates an appropriately cut blank of cardboard or the like, said blank being cut, scored and adapted to be 25 folded in such a manner, hereinafter described, as to form my improved display piece.

The blank comprises in general three sections, an upper or display section 2, an intermediate or base section 3, and a bottom or sub-base section 4. In the three sections illustrated, only the display section 2 and base section 3 are essential to my invention, section 4 being shown merely to illustrate one form which my invention may take.

35 The display section 2 is provided with a pleasing, artistic outline and is adapted to form an attractive background for an article of merchandise to be displayed. Intermediate the area of the section 2 a spaced pair of relatively narrow slots 5 and 6 are provided outlining a central panel 7. The slots 5 and 6 may take any desired form to impart to the lateral edges of the panel 7 a desired outline, and in addition, said slots outline opposite vertically disposed side pieces 8 and 9. The front face of the section 2 is scored along line 10 which extends horizontally from the top of slot 5 to the top of slot 6. Spaced in parallel relationship with the score-line 10 is a score-line 11 cut on the rear face of 50 panel 7. A score-line 12 divides the panel 7 from the base section 3, said score-line being cut on the rear face of the blank between the lower ends of the slots 5 and 6. Side piece 8 is separated from the base section 3 by score-line 13, 55 and similarly side piece 9 is separated from base

3 by score-line 14, both of said scores being cut upon the rear face of the blank.

The side-pieces 8 and 9 are scored, respectively, at 15 and 16, said scores being cut on the front face of the blank, and being disposed substantially parallel to score-lines 13 and 14. A substantially circular aperture 17 is provided in the upper portion of the panel 7 and opens into an aperture 18 provided in the head 19 of the section 2.

10 The arrangement is such that section 2 can be folded along the various score-lines in the following manner: The panel 7 is folded along line 10 in a rearwardly direction; panel 7 is folded along line 11 in a forwardly direction; and panel 7 is folded along line 12 in a forwardly direction. Side pieces 8 and 9 are respectively folded along lines 13 and 14 in a forwardly direction, and along lines 15 and 16 in a rearwardly direction. In other words, wherever the score 20 appears on the face of the blank, the fold is rearwardly and when the score appears on the rear of the blank the fold is forwardly.

25 In so folding the section 2 the side pieces are brought forwardly between the score-lines 13 and 15 and 14 and 16 respectively and portions 20 and 21 included between said lines are adapted

30 to occupy a position in plane-parallel relationship with base 3. The side pieces 8 and 9 are

35 then disposed at right angles to the portions 20 and 21, respectively and, hence, are disposed at right angles to the plane of the base 3. To permit these folding operations to be performed, the panel 7 must be simultaneously folded about the lines 10, 11 and 12. This disposes lines 11 and

40 12 in the plane of the panel 7 and line 10 in the plane of the side-pieces 8 and 9, and head 19 and the portion 22 included between lines 10 and 45 11 will be disposed parallel to the plane of the base. In other words, the panel 7 will be offset 40 rearwardly from the plane of the side-pieces and head. A recess or alcove 23 is thus provided.

45 When in display position, base-piece 24 is disposed horizontally and is adapted to support a conventional bottle 25, the neck 26 of which is positively engaged in apertures 17 and 18. When

50 the bottle 25 is not in position, as described, the display will collapse and topple over since no locks are provided. However, when the bottle is in display position, the display is locked by the engagement of the neck of the bottle with the apertures 17 and 18.

55 This construction has decided advantages in that it is not necessary to provide a lock and setting up the display is accordingly simplified,

in addition to the economy gained in the elimination of the lock-cutting operation. Further, in the use of many displays, actual bottled merchandise is employed and frequently said merchandise is stolen. If the bottle 25 is removed by an unauthorized person, the display immediately collapses, indicating to the shopkeeper that the goods have been removed. This provides the shopkeeper with the possibility of apprehending the guilty party.

It is to be understood that my invention contemplates the provision of one or more recesses or alcoves 23 in the same display piece or provision whereby one or more bottles may be disposed in the same recess or alcove.

Utilizing the fundamentals of the display construction hereinbefore described it is possible to surmount the same upon many attractive sub-bases. For purposes of illustration one specific 20 type of sub-base is hereinafter described.

Referring again to Fig. 1, the base 3 may extend beyond the width of the display proper, that is, beyond the base piece 24 at each end thereof to provide extensions 27 and 28. Said extensions 25 adjacent the base-piece 24 are provided with a plurality of transverse closely spaced score-lines 29 which are cut upon the rear face of the blank, the cuts being relatively shallow, whereby those portions of the extensions may be bent in an arc 30 transverse to the score-lines 29.

The sub-base portion 4 of the blank is separated from the base-piece 24 by score-line 30 which is cut upon the front face of the blank. The sub-base is divided into separate panels 31, 35 32 and 33 by score-lines 34 and 35, each of which is cut upon the front face of the blank. A tab 36 extends outwardly from the panel 33 and is adapted to lie in the same plane with panel 33. On each side of tab 36, a tab 37 and 38 are formed 40 which are divided from panel 33 by score-lines 39 and 40 respectively, said score-lines also being cut on the front face of the blank.

The sub-base section is adapted to be folded along score-lines 30, 34, 35, 39 and 40 whereby the panel 31 forms the front face of an enclosed box-like structure, panel 32 forming the bottom thereof and panel 33 forming the rear face. Tabs 37 and 38 are adhesively united to the bottom or rear face of the base-piece 24 and tab 36 is adhesively united to the rear face of panel 7, as shown best in Figs. 3 and 6.

When the sub-base is thus assembled, the extensions 27 and 28 provide the end closures for the sub-base, box-like structure. Extensions 27 and 28 are provided with score-lines 41 and 42 which permit the ends of the extensions to be folded beneath the sub-base. A tab 43 and 44 is formed at the ends of the extensions 27 and 28, 60 respectively, each of said tabs being provided with a pair of laterally extending tongues 45 and 46. The tabs 43 and 44 are divided from the remainder of the extensions 27 and 28 by score-lines 47 and 48, respectively. An aperture 49 and 50 is provided in the bottom panel 32 adjacent each end thereof, said apertures being of substantially rectangular shape.

To maintain the sub-base in box-like assembly, tabs 43 and 44 are folded along lines 47 and 48, 70 respectively, and each pair of tongues 45 and 46 are crease scored and bent toward each other. The ends of the tongues 45 and 46 are then inserted in apertures 49 and 50, respectively, and due to their inherent resiliency, and due to the 75 crease scoring, the tongues within the box-like

sub-base flare outwardly and provide an efficient lock, as shown best in Figs. 3 and 6.

It is to be understood, of course, that my invention needs no sub-base at all, but if a sub-base is desired, any type of suitable sub-structure 5 is contemplated.

The display in its fundamental form, that is, comprising sections 2 and 3 can be readily knocked-down or folded flat for purposes of shipping. Likewise, the complete display, illustrated 10 and described, even after gluing, can be folded flat for shipment merely by disengaging the locking tongues from apertures 49 and 50.

I claim as my invention:

1. A foldable display constructed of a one- 15 piece foldable material comprising a relatively flat base section, a display section integral with, and foldably connected to said base section and adapted to be disposed at an angle thereto, said display section comprising a plurality of portions 20 including a front portion and a rear panel, a section foldably connecting the front portion and rear panel together, said section being disposed in spaced relationship to said base section, said front portion being provided with an aperture 25 connecting with an aperture provided in said connecting section, said apertures being adapted to embrace the neck of a bottle at a point adjacent its mouth, said bottle being supported upon 30 said base section.

2. A foldable display constructed of a foldable material comprising a relatively flat base section, a display section integral with, and foldably connected to said base section and adapted to be disposed at an angle thereto, said display section 35 comprising a plurality of portions including a front portion and a rear panel, a section foldably connecting the front portion and rear panel together, said section being disposed in spaced relationship to said base section, said front portion 40 being provided with an aperture connecting with an aperture provided in said connecting section, said apertures being adapted to embrace the neck of a bottle at a point adjacent its mouth, said bottle being supported upon 45 said base section.

3. A display constructed of a foldable material comprising a relatively flat base section, a display section integral with, and foldably connected to said base section, said display section comprising a plurality of portions including a front portion 50 and a rear panel, a section hingedly connecting the front portion and the rear panel, a section hingedly connecting the front portion and the base section whereby said front portion and rear panel may be disposed in different planes, said front portion being provided with an aperture connecting with an aperture provided in said section 55 connecting the front portion and rear panel to embrace the neck of a conventional bottle at a point immediately below its mouth, said bottle 60 being supported upon said base section.

4. A display constructed of a foldable material comprising a relatively flat base section, a display section integral with, and foldably connected to said base section, said display section comprising 65 a plurality of portions including a front portion and a rear panel, a section hingedly connecting the front portion and the rear panel, a section hingedly connecting the front portion and the base section whereby said front portion and rear panel may be disposed in different planes, said front portion being provided with an aperture connecting with an aperture provided in said section 70 connecting the front portion and rear panel to embrace the neck of a conventional bottle at a point immediately below its mouth, said bottle 75 being supported upon said base section.

bottle at a point immediately below its mouth, said bottle being supported upon said base section, said entire display being foldable into a relatively flat position when said bottle is removed.

5. A display constructed of a foldable material comprising a relatively flat base section, and a display section comprising a rear panel and a front portion, said display section being adapted to be disposed at an angle to said base section and 10 being foldably connected thereto, a section foldably connecting the front portion and rear panel

together, said connecting section being disposed in spaced relationship to said base section, said front portion being provided with a substantially circular aperture connecting with an aperture provided in said connecting section, the aperture in said connecting section being adapted to receive the neck of a conventional bottle supported upon said base section, and being of lesser width than the diameter of the bead formed upon the mouth of said bottle.
